UNITED STATES PATENT OFFICE.

SYLVESTER GRAY, OF LONG ISLAND CITY, NEW YORK.

REFRIGERATOR.

SPECIFICATION forming part of Letters Patent No. 288,427, dated November 13, 1882.

Application filed August 25, 1883. (No model.)

To all whom it may concern:

Be it known that I, SYLVESTER GRAY, a citizen of the United States, and a resident of Long Island City, in the county of Queens and State of New York, have invented a certain new and useful Improvement in Refrigerators; and I do hereby declare that the following is a full, clear, and exact description of the invention, which will enable others skilled in the art to which it appertains to make and use the same, reference being had to the accompanying drawings, which form a part of this specification, and in which—

Figure 1 is a perspective view of a refrigerator provided with my improvement, showing the door open; and Fig. 2 is a vertical sectional view, on an enlarged scale, through the middle of the door on line $x x$ in Fig. 1.

Similar letters of reference indicate corresponding parts in both the figures.

My invention has relation to refrigerators, and it consists in the improved construction of a refrigerator-door, as will be hereinafter more fully described and claimed, whereby I dispense with the objectionable use of nails or tacks for fastening the zinc lining to the inside of the door.

In the accompanying drawings, A denotes the frame of my improved refrigerator-door, which is grooved, as usual, for the insertion of the door-panel B.

C is the door-band, which is made in four strips—one for each of the sides of the door, one for the top of the same, and one for the bottom—the bands being mitered at the corners, so as to fit closely together. This door-band should be of a width corresponding to the thickness of the finished door, and has a double rabbet, D E, adapted to fit a double rabbet in the door-jamb. The inner side of the door is formed, as usual, by a sheet of zinc, G, the

edge of which is inserted into a narrow groove, F, made on the inner side of the door-band C. The filling shown at H is confined on one side by the door-frame A and the panel B; on the other side, or the side facing the interior of the refrigerator, by the sheet of zinc G, and on the top and bottom and both sides by the door-band C. By this method of fastening the inside lining of the door—viz., by inserting its edges into the groove F in the door-band—it is securely fastened in place without the use of nails or tacks, which are apt to become rusty or to get loose by shrinkage of the wood into which they are inserted, thus loosening the inside lining and letting the filling out. All the nails or screws required in the construction of my improved refrigerator-door are those which fasten the door-band C and the door-frame A together, one of which is shown at I.

Having thus described my invention, I claim and desire to secure by Letters Patent of the United States—

The improved refrigerator-door herein shown and described, consisting of the outer door-frame, A, having panel B, the double-rabbeted door-band C, encircling the door-frame, overlapping it on the inner side, and provided with the groove F, the metallic inner face or door-lining G, inserted with its edges into the band-groove F, and filling H, constructed and combined substantially as and for the purpose shown and set forth.

In testimony that I claim the foregoing as my own I have hereunto affixed my signature in presence of two witnesses.

SYLVESTER GRAY.
